COLLAPSIBLE VEHICULAR WORK TRAILERS

David H. Tilley, St. Louis County, Mo.

Application October 9, 1950, Serial No. 189,215

3 Claims. (Cl. 296—24)

This invention relates in general to certain new and useful improvements in collapsible vehicular work trailers and, more particularly, to a trailer adapted for use as a mobile work station for use by a crew of men engaged in applying external stone-simulative facings to building structures.

In the application of stone-simulative facings to buildings it is necessary to provide the work crew with a series of molds in which the plaster-like cement mix is applied to the building surface. This work is ordinarily carried out by making up a batch of cement and sand mixture in the form of a viscous paste, or so-called "mud," as it is commonly referred to in the trade. The molds, which take the form of shallow aluminum pans, the inner faces of which are contoured to simulate cut stone or other masonry work, are usually lined with a thin sheet of wax paper which serves the dual function of facilitating separation between the mold and the applied "mud" and also of protecting the "mud" from sagging or staining. If the stone-simulative element is to be colored it is desirable to sprinkle finely ground mica and other powdered siliceous materials on the face of the paper before filling the mold with the "mud." In carrying out this type of work a number of different sizes and shapes of molds are used in order that the applied segments of stone-simulative material will be variegated very much in the manner of real stone which has been laid into the wall by a stone mason.

It will be apparent that the facing of buildings with stone-simulative coatings, as briefly described above, is a type of work requiring a highly unique set of tools and equipment which must be transported from the contractor's workshop to the site at which the job is being performed. In addition the materials for mixing the mud must be handy and the racks or fixtures into which the molds can be set while being filled also should be available as close as possible to the wall which is being surfaced so as to eliminate needlessly wasted steps and excessive handling.

It is, therefore, one of the primary objects of the present invention to provide a vehicular trailer which is uniquely constructed so as to be adapted for use by a crew of workmen as a mobile workshop in which all of the necessary tools and equipment for carrying out stone-simulative building facing jobs can be conveyed to the work site so as to be conveniently available.

It is another object of the present invention to provide a vehicular trailer which can be opened up quickly and simply to provide a relatively enclosed workshop equipped with all the necessary molds for carrying out a stone-simulative building facing job.

It is another object of the present invention to provide a vehicular trailer of the type stated which is equipped with all the necessary materials to carry out a stone-simulative building facing job and which can be transported directly to the work so as to be located in convenient proximity thereto.

2

It is another object of the present invention to provide a vehicular trailer of the type stated which is uniquely constructed to be specifically adapted for the purposes stated and which is furthermore capable of simple and economical construction.

With the above and other objects in view, my invention resides in the novel features of form, construction, arrangement, and combination of parts presently described and pointed out in the claims.

10 In the accompanying drawings—

Figure 1 is a side elevational view of the vehicular trailer in fully opened up or operative position for use as a workshop at the construction site;

15 Figure 2 is a vertical sectional view taken along line 2—2 of Figure 1;

Figure 3 is a front elevational view of the vehicular trailer;

20 Figures 4 and 5 are fragmentary side elevational views showing the jack leg which forms a part of the present invention, the jack leg being in inoperative position in Figure 4 and in downwardly disposed or operative position in Figure 5.

25 Referring now in more detail and by reference characters to the drawings, which illustrate a preferred embodiment of the present invention, A designates a vehicular trailer which comprises an oblong-rectangular chassis including two longitudinally extending parallel side channels which are transversely connected by cross channels 3 welded at their ends to the side channels 2.

30 At the forward end, the transverse channel 3 and side channels 2 are welded to the ends of forwardly extending inwardly converging drawbar braces 4, 5, which meet in forwardly spaced relation to the transverse channel 3 along the extended center line of the frame 1 and are

35 welded to each other and to a drawbar 6 which extends forwardly and rearwardly therefrom, and is, at its rearward end, welded to the central portion of the cross channel 3. At its forwardly projecting end the drawbar 6 is provided with a conventional trailer-hitching element 7.

40 Mounted upon and extending across the upper face of the chassis 1 is a floor 25 provided with two vertically extending end walls 26, 27, and a longitudinally extending back wall 28. Hingedly mounted to the upper margin of the back wall 28 is a top wall 29 which extends horizontally across the trailer in upwardly spaced parallel relation to the floor 25 and rests, along its transverse margins, on the upper horizontal margins of the end walls 26, 27, terminating in a longitudinal margin which

45 is coincident with the opposite margin of the floor 25. Rigidly secured to the top wall 29 is a side wall 30 which extends downwardly therefrom and closurewise across the side of the trailer and in opposed parallel relation to the side wall 28. It should be noted that the trailer is

50 approximately as high as it is wide so that the vertical dimensions of the side walls 28, 30, are substantially equal to the width of the trailer for purposes presently more fully appearing.

55 Hingedly mounted to the top wall 29 and normally extending along the under face thereof in inwardly spaced relation to the end walls 26, 27, are front and rear fly-walls 31, 32. By reference to Figures 1 and 2 it will be seen that when the top wall 29 and the side wall 30 are swung upwardly so that the top wall 29 is in vertical

60 alignment with the side wall 28, the side wall 30 will extend laterally therefrom in the formation of a roof and the fly-walls 31, 32, may be swung outwardly into vertically aligned coincidence with the end walls 26, 27. It will be noted that the fly-walls 31, 32, are hinged

65 to the top wall 29 in such a manner that their bottom edges will rest upon the top edges of the end walls 26,

27, and the top edges will rest supportingly against the under face of the roof-forming side wall 30. The fly-walls 31, 32, are furthermore provided with vertically shiftable bolts 33 which may be slid downwardly into locked engagement into keepers 34 rigidly mounted upon the inner faces of the end walls 26, 27, adjacent the upper margins thereof. When the bolts 33 are engaged in the keepers 34 the entire structure will be rigidly locked in opened position forming a sort of shed-like enclosure having a floor, a roof, a back wall, and two side walls and being open across one face, as shown in Figures 1 and 2.

Disposed within the body of the trailer and extending across the side wall 28 between the end walls 26, 27, is a work table 35 located in slightly downwardly spaced relation to the top wall 29 when the trailer A is closed up. The work table 35 is provided with three recessed shallow mixing basins 36, 37, and 38 and a central supporting leg 39 which serves to reinforce the workbench or table 35 and enable it to support a substantial load. In the area between the rearwardly disposed end wall 26 and the supporting leg 39 beneath the work table 35 is a series of spaced parallel shelves 40 and partitions 41 which, in effect, form pigeon-holes for the molds which are used in the formation of a stone-simulative building facing. In the space beneath the mixing basin it is possible to carry various drums or containers for storing the cement, coloring powder and other materials which are employed in this type of work.

Preferably, though not necessarily, the side walls 28, 30, are provided upon their outer faces with wheel enclosing fenders 42 of more or less conventional design. It will be noted in this connection that when the trailer is opened up the fender 42 which is associated with the side wall 30 will be on top of the entire structure, as best seen in Figure 1.

Swingably mounted upon the drawbar braces 5, 6, are jack legs 43, 44, each provided with downwardly swinging ends with relatively large disc-like foot pads 45. When the trailer is opened up for use as a workshed the jack legs 43, 44, may be swung downwardly into ground engaging position, as shown in Figure 5, thereby supporting the trailer in relatively horizontal position as a stable work-platform.

It should be understood that changes and modifications in the form, construction, arrangement, and combination of the several parts of the vehicular trailers may be made and substituted for those herein shown and described without departing from the nature and principle of my invention.

Having thus described my invention, what I claim and desire to secure by Letters Patent is:

1. A vehicular trailer comprising a wheel-mounted chassis having a floor, a forward end wall, a rearward end wall, a longitudinally extending side wall connecting the end walls along one side of the vehicle, a top wall hingedly connected to the side wall and extending across the upper margins of the end walls in upwardly spaced parallel relation to the bottom wall, a second side wall rigidly mounted at its upper margin to the outer margin of the top wall and extending closurewise downwardly therefrom between the end walls, said top wall and second side wall being adapted to swing upwardly as a unit so that the top wall forms a vertical upward extension for the first side wall and the second side wall becomes a roof-like member, wall forming end wings hingedly connected to the opposite margins of the top wall and being adapted, when the latter is disposed in

closure-wise position, to fold inwardly into underlying relation with respect thereto and be also adapted to fold outwardly, when the top wall is in vertical position, into edgewise engagement with the second side wall and the upper margins of the end walls respectively for supporting the top wall and second side wall in such upwardly disposed position, and means for optionally locking the end-wings in such top-wall supporting position.

2. A vehicular trailer comprising a wheel-mounted chassis having a floor, a forward end wall, a rearward end wall, a longitudinally extending side wall connecting the end walls along one side of the vehicle, a top wall hingedly connected to the side wall and extending across the upper margins of the end walls in upwardly spaced parallel relation to the bottom wall, a second side wall rigidly mounted at its upper margin to the outer margin of the top wall and extending closurewise downwardly therefrom between the end walls, said top wall and second side wall being adapted to swing upwardly as a unit so that the top wall forms a vertical upward extension for the first side wall and the second side wall becomes a roof-like member, and side wall forming end-wings hingedly connected to the top wall and being adapted when the top wall is in upwardly disposed position to swing outwardly into vertical alignment and edgewise abutment with the end walls.

3. A vehicular trailer comprising a wheel-mounted chassis having a floor, a forward end wall, a rearward end wall, a longitudinally extending side wall connecting the end walls along one side of the vehicle, a top wall hingedly connected to the side wall and extending across the upper margins of the end walls in upwardly spaced parallel relation to the bottom wall, a second side wall rigidly mounted at its upper margin to the outer margin of the top wall and extending closurewise downwardly therefrom between the end walls, said top wall and second side wall being adapted to swing upwardly as a unit so that the top wall forms a vertical upward extension for the first side wall and the second side wall becomes a roof-like member, and side wall forming end-wings hingedly connected to the top wall and being adapted when the top wall is in upwardly disposed position to swing outwardly into vertical alignment and edgewise abutment with the end walls, and a work-shelf mounted permanently within the vehicular trailer and extending horizontally between the end walls and along the first side wall, said shelf extending outwardly above the floor of the trailer for only a distance partially equal to the width thereof so as to provide a working space in front of the workbench wherein the workmen may stand.
